CLAIM

The ornamental design for [a bottom panel of] an enclosure for a peritoneal dialysis device, as shown and described.

DESCRIPTION

FIG. 1 is a front, top, and right perspective view of the [bottom panel of an] enclosure for a peritoneal dialysis device, showing the new design;

FIG. 2 is a front side elevational view thereof;

FIG. 3 is back side elevational view thereof;

FIG. 4 is a left side elevational view thereof;

FIG. 5 is a right side elevational view thereof;

FIG. 6 is a bottom plan view thereof;

FIG. 7 is a front, bottom, left perspective view thereof; and,

FIG. 8 is a back, bottom, right perspective view thereof.

The broken lines represent unclaimed portions of the [bottom panel of an] enclosure for a peritoneal dialysis device and form no part of the claimed design.

1 Claim, 7 Drawing Sheets

Matter enclosed in heavy brackets [ ] appears in the original patent but forms no part of this reissue; matter printed in italics indicates the additions made by reissue.
